UNITED STATES PATENT OFFICE

93,331

DESIGN FOR A RAZOR BLADE AND BATH- ROOM ARTICLE HOLDER

Jacob Cutler, Malden, Mass.

Application June 28, 1934, Serial No. 52,363

Term of patent 14 years

To all whom it may concern:

Be it known that I, JACOB CUTLER, a citizen of the United States, residing at Malden, in the county of Middlesex and State of Massachusetts, have invented a new, original, and ornamental Design for a Razor Blade and Bathroom Article Holder, of which the following is a specification, reference being had to the accompanying drawing, forming a part thereof.

I claim:

The ornamental design for a razor blade and bathroom article holder substantially as shown.

JACOB CUTLER.
